UNITED STATES PATENT OFFICE

CURT STEDEFELD, OF HEIDELBERG, GERMANY

RUNNING GEAR FOR HIGH-SPEED SUSPENSION CARS

Application filed October 25, 1926, Serial No. 144,071, and in Germany March 10, 1926.

In my former application No. 4,573, now Patent No. 1,602,464, granted October 12, 1926, a running wheel mounting for high speed suspension railways is described, in which the individual running wheels are borne at the ends of forked turning arms and oscillate therewith. If the car is to be driven not by an air propeller, but through the running wheels, then on the one hand the free play of the turning arms must not be hindered during up and down oscillation of the car body on the springs, and on the other hand the unsprung weight of the running gear must not be appreciably increased as this would nullify an essential purpose of the turning arm construction.

In consequence, wheel hub electric motors or flange motors, mounted on the end of the running wheel axle, cannot be used, since they would considerably increase the weight of the running gear. The bearer arm supported motors used in street railways cannot be used either, since a part of their weight would act as an increase of the unsprung weight and in addition would lead to a very complicated construction, since in addition to the forked arm the motor arms would have to be linked to the running wheel axle. A satisfactory solution for high speeds, that is for large motors, is only afforded by a fixed mounting of the motor on the sprung running frame or car body. Such arrangements are known in electric railway locomotives in the form of chassis motor constructions, either a connecting and coupling rod gear, or a single shaft yieldable in all directions, (e. g. spring couplings of the A. E. G. high speed railway and Westinghouse Company, or the double driving rod coupling of Ganz & Co. Bützli, Maschinenfabrik Oerlikon, or the Cardan shaft through hollow wheel axles of the Tschanz construction etc.), for power transmission to the wheels without hindrance to the spring action.

In consideration of the passengers the springing must be much more flexible, that is the spring movement must be much greater, in suspended driving vehicles than in standing railway locomotives. In the above driving methods this condition leads to incon-

venient constructional forms and to inconveniently large dimensions, from which results an undesirable increase in unsprung weight and an increase of size of the vehicle profile, that is an increased air resistance, particularly objectionable at high running speeds.

The present invention provides a drive for running wheels mounted in turning arms, which while of the most simple character and only increasing very slightly the unsprung weight, ensures a very high degree of reliability and safety. According to the invention the drive is effected by a toothed wheel of as light weight as possible, secured on the axle to be driven with which wheel meshes a drive transmitting wheel mounted coaxially with the axis of oscillation of the turning arm.

Several embodiments of such a drive are shown in the accompanying drawings, in which

Fig. 1 is a fragmentary side elevation, with parts shown in section, of one track wheel and its driving and supporting members,

Fig. 2 is a vertical section taken through the pivotal axis of the hanger arm in Fig. 1,

Fig. 3 is a fragmentary plan view of Fig. 1, with parts shown in horizontal section,

Fig. 4 is a side elevation of two forms of resilient drive,

Fig. 5 is a sectional view, on line B—B of Fig. 6, of another form of resilient drive wheel,

Fig. 6 is a vertical central section through the drive wheel shown in Fig. 5,

Fig. 6^a is a vertical central section through a drive wheel wherein alternate plates are shown as secured to the hub and the rim,

Figs. 7^a, 7^b are central sections illustrating two other forms of resilient drive, of the small gear of Fig. 4,

Figs. 8 and 9 are fragmentary side and horizontal section views, respectively, of another form of wheel support and resilient drive, and

Figs. 10 and 11 are similar side elevation and horizontal section views of another modification of the resilient drive.

The drive illustrated in Figures 1 to 3 shows a toothed wheel *b* secured on the run-

ning axle *a*, with which meshes a toothed wheel *c*, the axis of which is collinear with that *d* of the turning arm *e*. This method of drive permits the motor to be completely fixed on the sprung part of the car, either the running frame *f* or the car body. The teeth of the wheels *b* and *c* remain constantly in proper mesh during the greatest oscillations of the carrying arm *e* with the carrying spring *g* in relation to the running frame *f* or the car body.

It will be seen that the unsprung weight is only increased by the very light toothed wheel *b*. At the same time the kicks of the axle *a* due to the up and down oscillations about the axis *d* will be transmitted back to the wheel *c* and to the transmission gear and motor parts coupled thereto. These disadvantageous oscillations can almost entirely be eliminated by the interposition of a flexible spring connection between the wheel *b* and its hub *h*, or between the wheel *c* and its hub *i*.

Such spring connections in the form of leaf springs *k* or coil spring *l* are illustrated in Figure 4.

This springing arrangement known in itself, is also usable in essence for the present purpose. The resilience of the spring connection necessary here in view of the large angle of movement on both sides of the turning arm *e*, is, however, comparatively large (see Figure 1). The use of usual spring systems for such a resilience leads to excessive dimensions and inconvenient forms of construction. These are avoided by the arrangements shown in Figures 5 to 7.

For comparatively small wheels according to Figures 5 and 6, the spiral bending springs *m*₁ and *m*₂ provide the necessary large resilience, while they are mounted pair-wise one within the other to obtain rotational and torque balance. They are secured at their inner ends for example by bolts *n* to the hub *o*, at their outer ends by bolts *p* to the toothed rim *q*. The latter can be guided on the hub *o* by cover plates *r*, either cylindrically, or spherically, to obtain automatic adjustment in relation to the teeth on the meshing wheel, in known manner. This spring system can be damped, without the addition of special moving parts, if the spiral springs are not originally made flat, but are wound with the individual turns laterally displaced, so that when mounted between the flat cover plates *r* they are to a certain extent preliminarily torsionally loaded and produce a perceptible lateral frictional action. Preferably wear receiving friction plates *s* are arranged between the springs *m*₁, *m*₂ and the cover plates *r*. The damping effect can be multiplied by mounting reverse friction plates *s* on one another, alternately coupled with the hub *n* and the rim *q*, in the manner of the known multiplate clutches.

With toothed wheels with a large breadth in relation to diameter, as is shown by the wheel *c* in Figures 1 to 4 a high utilization of the spring weight and space is achieved both in springing and in damping, when ring springs *t* according to Figure 7 are used in the embodiment of Figure 4, in the same way as such have been lately used for example in railway buffers and couplings. In view of the practically pure tension or compression stresses, these have a greater resilience per unit volume than any other springing system; in addition they can be constructed with a high degree of self damping, which can be regulated over a large range according to need, particularly when they are combined with cylindrical coil springs (Figure 7).

In the half section Figure 7^a for example an external coil spring *u* is combined with an internal circular spring of closed rings *t* of high self damping against one another. Naturally the ring spring *t* could be external and the coil spring *u* internal.

The half section Figure 7^b shows another example in which two external springs are arranged in series; a divided coil spring *v* and a ring spring *w*₁. In the latter only the outer rings *w*₁ are closed, the inner rings *w*₂ being cut through so that they bear on the guide sleeve *x* and produce damping friction. The mounting of the ring spring *w*₁ in the centre of the whole system gives it a particularly large friction space on the guide sleeve *x*.

When space or similar conditions require, naturally the toothed wheels *b* and *c* on the running and turning arm axles can be unsprung and the spring connection is then interposed in the following transmission members.

The embodiments of Figures 8 to 11 are notably efficient. In Figures 8 and 9 the toothed wheels *b* and *c* on the running axle *a* and the turning arm axis *d*—*d* are on one side of the running gear, the remaining transmission members, e. g. the bevel wheel *y* on the other side. They are connected by a shaft *a'* passing through the hollow turning arm spindle *z*. The shaft *a'* can, in known manner, be made of high quality material and so dimensioned that its torsional elasticity is sufficient to take up the angular motion of the turning arm *e*.

In the form shown in Figures 10 and 11, the wheels *b* and *c* as well as the next transmission wheels *b'* all lie on the same side of the running gear. The spring connection *c'* here is of a usual or above described kind and is interposed between the wheels *b'* and *c*.

If, as is shown in my former application, two running wheels with turning arms are mounted to form a single running gear, both running wheels can be driven individually or in common, in one of the above described ways. In this case the two driving gears can

be connected by intermediate wheels or by the motor itself.

What I claim is:—

1. In a wheeled vehicle, a driving mechanism of the type including a frame, a hanger arm, a driving wheel journaled on said hanger arm, a drive for said wheel including a gear rigidly secured to said wheel, means pivotally mounting said hanger arm on said frame, a driven gear in mesh with said first gear and having an axis coinciding with the pivotal axis of said hanger arm, the pivotal mounting of said hanger arm restraining all movement thereof except in a vertical plane, whereby the teeth of said gears remain fully in mesh upon vertical movement of said hanger arm, characterized by the fact that means is provided for resiliently driving said gears, whereby vertical movement of said wheel with reference to said frame is not transmitted through said gears to the prime mover.

2. The invention as set forth in claim 1, wherein the said means comprises spring means connecting the rim of one gear to the hub thereof.

3. In a wheeled vehicle, a driving mechanism of the type including a frame, a hanger arm pivotally mounted on said frame, a running wheel journaled on said hanger arm, and resilient means for transmitting a part of the vehicle load to said running wheel, and a drive for said wheel comprising a gear rigidly secured to said wheel and in mesh with a driven gear having an axis coinciding with the pivotal axis of said hanger arm characterized by the fact that means is provided for resiliently driving said gears, whereby vertical movement of said wheel with reference to said frame is not transmitted through said gears to the prime mover wherein the said means comprises a spring connecting the rim of each of said gears to its respective hub.

4. In a wheeled vehicle, a driving mechanism of the type including a frame, a hanger arm pivotally mounted on said frame, a running wheel journaled on said hanger arm, and resilient means for transmitting a part of the vehicle load to said running wheel, and a drive for said wheel comprising a gear rigidly secured to said wheel and in mesh with a driven gear having an axis coinciding with the pivotal axis of said hanger arm characterized by the fact that means is provided for resiliently driving said gears, whereby vertical movement of said wheel with reference to said frame is not transmitted through said gears to the prime mover, wherein said means comprises two spiral springs connecting the rim of one gear to its hub, and symmetrically arranged with respect to a plane through the axis of the gear.

5. The invention as set forth in claim 1, wherein the said means comprises a damped spring connecting the rim of one wheel to its hub.

6. In a wheeled vehicle, a driving mechanism of the type including a frame, a hanger arm pivotally mounted on said frame, a running wheel journaled on said hanger arm, and resilient means for transmitting a part of the vehicle load to said running wheel, and a drive for said wheel comprising a gear rigidly secured to said wheel and in mesh with a driven gear having an axis coinciding with the pivotal axis of said hanger arm characterized by the fact that means is provided for resiliently driving said gears, whereby vertical movement of said wheel with reference to said frame is not transmitted through said gears to the prime mover, wherein said means comprises two spiral springs connecting the rim of one gear to its hub, and plates pressing against the lateral edges of said springs to damp the movement thereof.

7. The invention as set forth in claim 1, wherein said means comprises two spiral springs connecting the rim of one of said gears to its hub, the said springs being normally of conical form, a plurality of plates at each side of said springs and pressed against the same to retain the same in the form of cylindrical spirals, alternate plates being secured to the rim and the hub of said gear, respectively.
